UNITED STATES PATENT OFFICE

152,519

DESIGN FOR A BLANKET OR SIMILAR FABRIC ARTICLE

Maurice D. Cramer, Chicago, Ill.

Application January 26, 1948, Serial No. 144,049

Term of patent 7 years

(Cl. D92—2)

To all whom it may concern:

Be it known that I, Maurice D. Cramer, a citizen of the United States, residing in Chicago, Cook County, Illinois, have invented a new, original, and ornamental Design for a Blanket or Similar Fabric Article, of which the following is a specification, reference being had to the accompanying drawing, forming a part thereof.

The figure is a plan view of a blanket or similar fabric article showing my new design.

I claim:

The ornamental design for a blanket or similar fabric article, substantially as shown.

MAURICE D. CRAMER.
